CLAIM

The ornamental design for a pet shoe, as shown and described.

DESCRIPTION

FIG. 1 is a front, bottom perspective view of a pet shoe, showing my new design;

FIG. 2 is a top, rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged, perspective view of detail “9”, identified in FIG. 1.

In the drawings, the equal-length broken lines depict portions of the pet shoe that form no part of the claimed design. The dash-dot-dash broken lines depict stitching on the pet shoe that forms no part of the claimed design. All broken lines form no part of the claim.

1 Claim, 9 Drawing Sheets
